UNITED STATES PATENT OFFICE.

GEORGE B. FRALEY, OF PHILADELPHIA, PENNSYLVANIA, ASSIGNOR TO
ELIZABETH S. GALBRAITH, OF PHILADELPHIA, PENNSYLVANIA.

MOTOR.

SPECIFICATION forming part of Letters Patent No. 740,117, dated September 29, 1903.

Application filed July 14, 1902. Serial No. 115,409. (No model.)

To all whom it may concern:

Be it known that I, GEORGE B. FRALEY, a citizen of the United States, residing in the city and county of Philadelphia, State of Pennsylvania, have invented a new and useful Improvement in Motors, of which the following is a specification.

My invention consists of an improved construction of a motor that is designed to use a liquefied gas as the propelling medium; and it consists of a novel construction of a motor by which I obviate the employment of stuffing-boxes or packing to confine the gas.

My invention also consists of a novel arrangement of valves and valve-gear and, further, in various novel features of construction hereinafter fully described and claimed.

Figure 1 represents a partial side elevation and vertical section of a motor constructed in accordance with my invention. Fig. 2 represents a plan of a portion of the valve-operating mechanism. Fig. 3 represents a vertical section of the end of one of the cylinders. Fig. 4 represents a vertical section thereof,

25 taken on the line $x-x$ of Fig. 3. Fig. 5 represents a perspective view of the cylinder-head, taken from the inner side. Fig. 6 represents a perspective view of an insulating-cup that is situated within the cylinder-head.

30 Fig. 7 represents a plan view of the valve-gear and valve. Fig. 8 represents a side elevation of the valve-gear. Fig. 9 represents a horizontal section of the valve, taken on the line $y-y$ of Fig. 13. Fig. 10 represents a

35 similar view, but with the valve in a different position. Fig. 11 represents a horizontal section of the valve, taken on the line $z-z$ of Fig. 14. Fig. 12 represents a similar view, but with the valve in a different position.

40 Fig. 13 represents a fragmentary section of the valve, taken on the line $x'-x'$ of Figs. 7 and 9. Fig. 14 represents a vertical section taken on the line $y'-y'$ of Figs. 7 and 11. Fig. 15 represents a perspective view of the valve, 45 taken from its lower side. Fig. 16 represents a side elevation thereof.

Similar numerals of reference indicate corresponding parts in the figures.

Referring to the drawings, 1 designates a 50 reservoir or tank communicating with a suitable source of supply by means of a pipe 2

and with the pumps 3 and 4 by means of the pipes 5. These pumps 3 and 4 are provided with the usual suction and discharge chambers and with a passage 6, leading to the cylinder 7, and also with a discharge-pipe 8.

Within the cylinder 7 are the pistons 9, that are caused to move in unison by the common piston-rod 10, which passes through the ends of the cylinder in which the water 60 is drawn in and discharged. In the other ends of the cylinder and on the other sides of the piston the propelling medium is admitted, and I will now proceed to describe the construction by which I avoid the employment of a stuffing box or boxes and packing to confine this propelling medium, since I find that owing to its nature gasified liquefied gases are not controlled and confined by ordinary stuffing-boxes and packings to the 65 degree necessary in this connection. The outer head 11 of the cylinder is provided with an inlet and exhaust port 12, that communicates with the valve-casing 13, said valve-casing being provided with an exhaust-port 70 75 14 diametrically opposite, and the upper end of the valve-casing communicates with the pipes 15, said pipes 15 at each end of the roller communicating with a common pipe 16, leading to a source supplying a liquefied gas, 80 the state of which has been changed to a gas.

The valve 17, Figs. 15 and 16, is cylindrical and is carried by a rotatable stem 18, passing through the bottom of the casing 13 and connected with suitable mechanism for partially 85 rotating or oscillating the same, hereinafter described. The valve 17 rests on the bottom of the valve-casing, the adjacent faces of these parts being suitably finished to form a tight joint that will prevent the passage of 90 the gas. To maintain the valve always upon its seat, the connection between the same and the stem 18 is not rigid, the same being secured by forming notches 19 in a screw-threaded boss 20 on the upper side of the 95 valve, in which is situated a pin 21, carried by the upper end of the stem, which permits the relative movement between the stem and valve, although causing said parts to rotate in unison. A cap 23 screws over the boss 20 and a tight joint is made by a packing-ring 24 between the cap and the valve. The valve

17 is provided with two ports, one, the port 25, that controls the inlet to the cylinder and which consists of an opening between the upper and lower sides of the valve, and the other 5 port, 26, consists of a channel or the inner side of the valve of sufficient length to join the ports 12 and 14 of the valve-casing.

In the outer head of the cylinder is a recess 27, in which I place the insulating-cup 28. 10 The head 11 and the cup 28 are provided with the openings 29 and 30, which I have shown as three in number, one communicating with the combined inlet and exhaust port 12, while the other two receive suitable insulated terminals-plugs 31 of an electric circuit, which are connected with an electric heater 32, lying within the cup 28. In controlling the inlet and exhaust of this propelling medium I find it desirable to operate the valves instantaneously to quickly open or close the inlet or exhaust, and I have shown one form of mechanism for accomplishing this purpose in a practical way, and I will now describe it.

The valve-stems 18 are provided with the 25 arms 33, that are pivotally connected with the vibratory rod 34, so that when this rod 34 is moved back and forth the valves 17 are oscillated, the extent of movement of the rod and the means for moving it being such that the 30 limit of the movement of said rod will alternately bring the valve-port 25 in communication with the port 12 and the port 26 in communication with the ports 12 and 14, thus alternately opening the inlet and the exhaust 35 from the cylinder. Conveniently mounted upon the top plate 35 of the reservoir 1 is a post 36, carrying the plate 37, to which is pivoted at 38 the vibratory member 39, one end of which is conveniently slotted, as at 40. One 40 end of the bell-crank lever 41, mounted on the pivot 42, has a pin situated within the slot 40, and the other arm of said bell-crank lever is pivoted to a block 43, rigid with the rod 34. The said vibratory member 39 is pivoted near 45 one edge to the plate and at equal distances on either side of the pivot is provided with the stops 44. The adjacent edge of the plate 37 is angular, the apex being midway between the stops 44 or opposite the pivot 38 to form the 50 cam-faces 45. Mounted at the other side of the plate 37 and also in alinement with the apex of the cam-faces 45 and the pivot 38 is the lever 46. The said lever is slotted, as at 47, to receive the pivot-pin 48, upon which it 55 vibrates. On the under side of the lever is a projection 49, conveniently an antifriction-roller, and which is long enough to extend across the edges of the plate 37, as well as the vibratory member 39, the location of the 60 same with relation to the slot 47 and pivot 48 being such that when said lever is at one limit of its throw and in engagement with one of the stops 44 of the vibratory member the pivot 48 is at the inner end of the slot 47, 65 while when the projection 49 is at the apex of the cam-faces 45 the pivot-pin is at the other end of said slot. Suitably mounted

with the swinging end of the lever 46 is a spring 50, the other end of which is connected to a stationary support, and the tendency 70 of said spring is to hold the inner end of the slot 47 against the pin 48, or, in other words, to hold the projection 49 against the cam-faces 45. The free end of said lever 46 is situated in the path of two projections 51 and 75 52, carried by a longitudinally-movable rod 53, the ends of which pass into the ends of the cylinder and are situated to be moved by the pistons 9.

The operation is as follows: When the parts 80 of the motor are in the position shown in Figs. 1, 2, 7, 8, 9, 11, 13, and 14, the left-hand cylinder is exhausting and gas is being supplied to the right-hand cylinder. As the pistons move in the direction shown by the arrow 85 the piston of the right-hand cylinder will contact with the end of the rod 53, and thereby move the projection 52, and the lever 46 will be moved in the direction shown by the arrows in Figs. 2 and 7 against the tension of the 90 spring 50. As the lever 46 is thus moved the projection 49 rides over the right-hand cam-face, also against the tension of the spring 50, and as soon as the projection 52 reaches the point shown in dotted lines in Fig. 7, 95 which is about the end of its stroke in this direction, the projection reaches the apex of the cam-faces, and as soon as it passes the same the tension of the spring 50 will draw it instantly along the left-hand cam-face, 100 causing it to contact with the edge of the vibratory member 39 and to turn this member on its pivot, the contact between said projection 49 and the left-hand stop 44 bringing the parts to a standstill; but when the vibratory 105 member 39 is vibrated it swings the bell-crank lever 41, which moves the rod 34 laterally and turns the arm 33 to such an extent that it will bring the ends of the valve-port 26 opposite the ports 12 and 14 of the valve-casing. This then reverses the position of the 110 valves, throwing the left-hand valve from the position shown in Figs. 7, 9, and 13 to the position shown in Fig. 10, while the right-hand valve, as shown by Figs. 7, 11, and 14, is 115 thrown to the position shown in Fig. 12, which causes the right-hand cylinder to exhaust and permits the propelling medium to enter the left-hand cylinder. When the piston in the left-hand cylinder contacts with the end 120 of the rod 53, it will cause the projection 51 to move the lever 46 in the opposite direction, and when it reaches the apex of the cam-faces it will again be quickly operated by the 125 spring 50 and throw the vibratory member 39 again to the position shown in full lines in Fig. 7, thus restoring the valves to the other position.

When the state of the liquefied gas is 130 changed to a gas, I prefer to employ heat to raise the temperature thereof and to increase the degree of expansion, and it is in this state that it enters the pipes 15 from the pipes 16; but to obtain the greatest expansive force

from this gas I propose to further superheat the same, and I have shown one way in which this can be conveniently accomplished — namely, by an electric heater placed in the 5 head of the cylinder and by means of which I am enabled to obtain an exceedingly high degree of temperature, which not only increases the expansive force, and consequently the power to be derived from the motor, but 10 also obviates freezing, which has been found to be a great objection to motors employing a propelling medium of this class.

Although in the drawings I have shown the 15 valve-gear arranged to make a full stroke, it will be understood that the gearing may be changed to cut off the propelling medium at any desired part of the stroke.

Having thus described my invention, what I claim as new, and desire to secure by Letters 20 Patent, is—

1. In a motor having a cylinder, a valve controlling the passage of the propelling medium thereto, and consisting of a valve-seat and a disk valve and a rotary stem connected 25 with said disk valve to rotate the same, the connection between said stem and valve permitting the movement of the valve longitudinally of its stem.

2. In a motor having a cylinder, a valve 30 controlling passage of the propelling medium, and consisting of a valve-seat and disk valve, a rotary stem connected with said disk valve to rotate the same, the connection between, said stem and valve permitting the movement 35 of the latter longitudinally of its stem, and means for sealing the upper side of said valve.

3. In a motor having a cylinder, a valve controlling the passage of the propelling medium thereto, and consisting of a valve-seat 40 and a disk valve, an opening through said valve and valve-seat, a rotary stem passing through said openings and connected with

said valve to rotate the same, the connection between said stem and valve permitting the movement of the latter longitudinally of said 45 stem, and a sealing-cap situated upon the outside of said valve and sealing the opening therethrough.

4. In a motor having a cylinder, a valve controlling the passage of the propelling me- 50 dium thereto, and consisting of a valve-seat having an opening therethrough, a disk valve having a boss on its outside provided with an opening, a rotary stem passing through said openings, and having projections loosely en- 55 gaging said valve, and a sealing-cap mounted upon said boss and sealing the opening through said boss.

5. The combination with the valves of a motor, and means connecting the same, of a 60 stationary cam, a vibratory longitudinally-movable lever engaging said cam, a spring connected with said lever, means actuated by the motor-pistons for turning said lever on its pivot, and a vibratory member connected 65 with said connection between the valves and adapted to be actuated by said lever.

6. The combination with the valves of a motor, and means connecting the same, of a stationary cam, a vibratory longitudinally- 70 movable spring-actuated lever engaging said cam, said lever being movable upon its pivot by reason of the movement of the motor-pis- 75 tons, a vibratory member situated adjacent said cam and in the path of said lever and provided with stops adapted to be engaged by said lever, said vibratory member being connected with said connection between the valves.

GEORGE B. FRALEY.
